US0D1030517S

(12) **United States Design Patent** (10) Patent No.: **US D1,030,517 S**
(45) Date of Patent: ** Jun. 11, 2024

(54) **CLINICAL THERMOMETER**

(71) Applicant: **Quanta Computer Inc.**, Taoyuan (TW)

(72) Inventors: **Barry Lam**, Taoyuan (TW);
Chia-Yuan Chang, Taoyuan (TW);
Jung-Wen Chang, Taoyuan (TW);
Juan-Jung Li, Taoyuan (TW)

(73) Assignee: **QUANTA COMPUTER INC.**,
Taoyuan (TW)

(**) Term: **15 Years**

(21) Appl. No.: **29/869,248**

(22) Filed: **Dec. 27, 2022**

(30) **Foreign Application Priority Data**
